UNITED STATES PATENT OFFICE.

CHARLES WITTENBERG, OF INDIANAPOLIS, INDIANA, ASSIGNOR TO EDWARD G. CORNELIUS, OF SAME PLACE.

RETURN ATTACHMENT FOR TELEPHONE TOLL-COLLECTORS.

SPECIFICATION forming part of Letters Patent No. 359,306, dated March 15, 1887.

Application filed September 9, 1886. Serial No. 213,055. (No model.)

To all whom it may concern:

Be it known that I, CHARLES WITTENBERG, a citizen of the United States, residing at Indianapolis, in the county of Marion and State 5 of Indiana, have invented a new and useful Improvement in Return Attachments for Telephone Toll-Collectors, of which the following is a specification.

My invention relates to an improvement in 10 that class of telephone toll-collectors in which the connection with the telephone apparatus at a subscriber's station is such that a coin must be deposited in the toll-collector before the telephone can be operated.

15 The object of my improvement is to provide means whereby the coin can be returned to the depositor by the operator at the exchange-station in case the desired connection with another subscriber cannot be made, as hereinafter fully described.

The accompanying drawings illustrate my invention.

Figure 1 represents a side elevation of my improvement applied to a telephone toll-collecting apparatus which forms the subject-matter of another application, No. 206,104, 25 the outside of the case covering the improvement having been removed. Figs. 2, 3, and 4 represent vertical sections on the line *a a*, Fig. 1, showing different positions of the working parts.

A represents the toll-collector shown in my above-mentioned pending application. It consists, essentially, of a sliding bar, *b*, which is 35 connected with the switch-lever and receiver-support *c*, so as to move up and down therewith, a locking-lever, *d*, (shown in dotted lines,) and a coin-chute, *e*, the arrangement being such that when a coin is placed in the 40 chute *e* it operates to disengage the locking-lever from the sliding bar and thereby release the switch-lever, the coin then passing direct from chute *e* to a locked drawer.

For the purpose of detaining the coin after 45 it leaves chute *e* and directing it either to the drawer *f* or to the return-chute *l*, I provide a short rectangular tube, *i*, which is pivoted at *j* to the case *B* in a position to receive the coin as it leaves chute *e*. Below tube *i*, in the lower 50 part of case *B*, are two chutes, *k* and *l*. Chute *k* is straight, and leads directly to the cash-

drawer *f*. Chute *l* is curved outward, and the outer end is closed, but cut away at the sides, so as to retain, but at the same time expose, the coin, as at *n*, Fig. 1.

55 D is an electro-magnet arranged in the same electric circuit with the telephone.

To the back of tube *i* is secured a soft-iron armature, *o*. Magnet *D* is arranged so that the armature *o* shall be within its field of attraction. A light spiral spring, *p*, is inserted in the core of the magnet and projects slightly therefrom, so that tube *i* stands normally over the partition *r*, between the chute *k* and *l*, the armature *o* resting against spring *p*, as in Fig. 65

2. Extending from the lower end of bar *b* is an arm, *s*, carrying a wedge, *t*, which engages a pin, *u*, which projects from the edge of tube *i*.

The operation of my device is as follows: 70 The telephone-receiver having been removed from the switch-lever *c*, and the telephone at a subscriber's station being in connection with the exchange-station, the tube *i* and arm *s* are in the position shown in Fig. 2. The coin, 75

passing from chute *e*, falls into tube *i*, and rests with its lower edge on the partition *r*, between chutes *l* and *k*. If the operator at the exchange-station finds that the connection desired by the subscriber cannot be made, he sends, by means of his "call-circuit," or a suitable battery, a strong electric current through the subscriber's line, thus energizing the magnet *D*, 80

which, drawing tube *i* toward it, brings the tube and coin *n* over chute *l*, as in Fig. 3. The coin falls into said chute, and, coming into 85 view, as in Fig. 1, is removed by the person at the telephone. If, however, the desired connection is made, tube *i* remains in its normal position until bar *b*, with its arm *s*, moving downward with the switch-lever when the telephone-receiver is hung up, brings wedge *t* in contact with pin *u*, and thus forces the tube *i* 90 outward over chute *k*, as in Fig. 4, and the coin passes through chute *k* to the drawer *f*.

I claim as my invention—

1. In a return attachment for toll-collectors, the combination of the stationary chute arranged to receive a coin, two auxiliary chutes arranged below said stationary chute, the intermediate swinging tube arranged to receive a coin from said stationary chute and to deliver the same to either of said auxiliary 100

chutes, the electro-magnet arranged to draw said tube into position to deliver its contents into one of the two auxiliary chutes, a moving part of a telephone apparatus, as the 5 switch-lever, and intermediate mechanism connecting said switch-lever and swinging tube, whereby the tube is swung into position to deliver its contents into the other of said chutes by the movement of the switch-lever, all arranged to co-operate substantially as specified.

2. The combination, with the stationary coin-receiving chute of a toll-collector and a stationary auxiliary chute arranged to receive the coin after leaving said chute, of an intermediate swinging tube arranged to receive the 15 coin from said receiving-chute, a stop arranged opposite the free end of said tube,

whereby the coin is retained therein, and an electro-magnet arranged to attract said tube and to draw it into position to deliver its contents into said auxiliary chute, substantially as specified.

3. In a return attachment for toll-collectors, the combination of tube *i*, having armature *o* and pin *u*, chutes *k* and *l*, partition *r*, 20 electro-magnet *D*, bar *e*, having arm *s*, and wedge *t*, all combined and arranged to co-operate substantially as and for the purpose specified.

CHARLES WITTENBERG.
